Des. 203,578

Patented Feb. 1, 1966

203,578

CONTAINER EDGE SUPPORTABLE PAINT BRUSH HOLDER

Anthony Cortina, 56 Huntington St., New London, Conn.

Filed June 3, 1964, Ser. No. 80,258

Term of patent 14 years

(Cl. D9—2)

FIG. 1 is a reduced perspective view of a paint brush holder showing my new design;

FIG. 2 is a side elevational view thereof, the fragmentary portions shown in broken lines being included for illustrative purposes only;

FIG. 3 is an elevational view as seen from the right of FIG. 2;

FIG. 4 is a top plan view; and

FIG. 5 is a bottom plan view.

I claim:

The ornamental design for a container edge supportable paint brush holder, substantially as shown and described.
